UNITED STATES PATENT OFFICE.

HENRY LEITNER, OF WESTMINSTER, LONDON, AND WILLIAM HERBERT EXLEY, OF MAYBURY HILL, WOKING, ENGLAND.

ELECTRIC ACCUMULATOR.

1,275,448.

Specification of Letters Patent. Patented Aug. 13, 1918.

Application filed February 1, 1918. Serial No. 214,978.

To all whom it may concern:

Be it known that we, HENRY LEITNER and WILLIAM HERBERT EXLEY, subjects of the King of Great Britain, respectively residing at 3 Victoria street, Westminster, London, England, and "The Rest," Maybury Hill, Woking, Surrey, England, have invented new and useful Improvements in Electric Accumulators, of which the following is a specification.

Our invention relates to plates or elements for electric accumulators, and to that class of plate comprising a support of an insulating material, such as celluloid, vulcanite, vulcanized fiber, wood, prepared wood or the like, which carries a metal conductor around which the active material is embedded.

Now, according to our invention, which has for its object improvements in plates or elements of this type, both of the single pole and double pole forms, we make use of a non-conducting support of wood, or wood-pulp, or other preparation of wood which is preferably of a porous nature, the said support being formed or provided with a series of rectilinear grooves, the adjacent grooves or spaces being separated by solid portions of the wood support, and each groove or space being designed to house within it a conductor embedded in active material. For example, the said support may be in the form of a plate having grooves on opposite faces.

In practice the positive and negative active materials may be applied to separate supports which are opposite to one another in the accumulator cell. Or, and preferably, these positive and negative materials may be applied to one and the same support, in which case the said two materials are separated from one another by the rods or ribs upon the preferably porous non-conducting support.

To enable our invention to be fully understood we will describe it by reference to the accompanying drawings, in which:

Figure 1 is a side elevation of a portion of a non-conducting support provided with an improved form of metallic conductor.

Fig. 2 is a side elevation of a portion of a non-conducting support provided with a modified form of metallic conductor.

Fig. 3 is a vertical section on the line 17—
17, Fig. 2.

Fig. 4 is a horizontal section of Fig. 1. 55
Fig. 5 is a horizontal section of Fig. 2.

Referring to the construction of plate or element shown in the drawing, *a* represents a plate or strip of wood as above referred to, *b* being vertical grooves which are cut, molded or otherwise formed in the said plate or strip *a* on the opposite faces thereof, these grooves being advantageously made with undercut sides as clearly shown in order to form a key for the active material *b*¹, shown 65 in Figs. 4 and 5. The central web or un-grooved portion of the plate *a* is furnished with a number of holes or perforations *c*, and through these perforations there are threaded metallic conductors, which are connected to the conducting strip *e* which forms the terminal of the element. 70

In practice, as before stated, the active material in adjacent grooves of the support is of opposite polarity, so that the element 75 formed will be bipolar.

The metal conductor, which is mechanically applied to the grooves *b* of the support as above described, is in the form of a stamped strip consisting of a central bar or 80 rib *i* having a number of laterally projecting tongues *j*, as shown. The tongues *j* extend through the holes *c* in the bottoms of the grooves *b* of the support *a*, the said tongues being then bent inward toward one another 85 in the opposite groove so that they assume the form shown in Fig. 4. An individual strip is introduced into each of the grooves on one side of the plate, the said strips being preferably stamped integrally with the terminal 90 strip *e*.

Figs. 2, 3 and 5 show a form of conductor which is similar to that shown in Figs. 1 and 4, with the exception that a single strip *i* extends down a groove *b* on one side of the 95 plate *a*, bends around the bottom thereof and passes up in the opposite groove. The tongues *j* in this construction extend through the holes *c* in the bottoms of the grooves *b* alternately from opposite grooves *b*. 100

What we claim and desire to secure by Letters Patent is:

1. An element for electric accumulators comprising a non-conducting support pro-

vided with grooves separated by solid portions of the support, and an electric conducting strip having tongues extending through apertures in said support and embedded in active material.

2. An element for electric accumulators, comprising a support of porous wood provided with grooves separated by solid portions of the porous supports, active material of one polarity located in one of said

grooves, and active material of opposite polarity located in an adjacent groove, said active material supporting conducting means, which are embedded therein.

HENRY LEITNER.

WILLIAM HERBERT EXLEY.
